UNITED STATES PATENT OFFICE.

JAMES J. WHITE, OF BOULDER, MONTANA.

BOTTLE-STOPPER.

No. 892,343.

Specification of Letters Patent. Patented June 30, 1908.

Application filed April 18, 1906. Serial No. 312,406.

To all whom it may concern:

Be it known that I, JAMES J. WHITE, a citizen of the United States, residing at Boulder, in the county of Jefferson, State of 5 Montana, have invented certain new and useful Improvements in Bottle-Stoppers; and I do hereby declare the following to be a full, clear, and exact description of the invention, such as will enable others skilled in 10 the art to which it appertains to make and use the same.

This invention relates to bottle stoppers, and more particularly to that class of devices of this nature in which the neck of the bottle 15 must be broken before its contents can be emptied. A disadvantage common to bottles of this nature is that the weakened portion of the neck is below the usual secondary or guard stopper and hence the neck, in such 20 bottles may be broken, the contents replaced by a substitute and the severed portion of the neck united to the bottle in the original position by means of heat.

The primary object of the present invention 25 is therefore to provide a bottle having an annularly grooved neck, the said groove serving to weaken the neck sufficiently to enable it to be broken and as a seat for the ends of a spring wire which is carried by the guard 30 stopper of the bottle, the said ends of the spring wire being adapted to spring apart when the neck is fractured and prevent rejoining of the parts thereof.

In the accompanying drawings:—Figure 1 35 is a vertical sectional view through the upper portion of a bottle showing the invention in position in the neck thereof. Fig. 2 is an elevation of the stopper. Fig. 3 is a transverse section through the stopper. Fig. 4 is 40 a sectional view showing the position which the spring arms assume when the neck of the bottle is broken.

Referring to the drawing more specifically, the numeral 5 denotes the neck of a bottle of 45 any desired construction and 6 an annular groove formed in the neck adjacent the lower end thereof, the groove being of such depth as to insure easy fracture of the neck. Located in the neck 5 directly below the groove 50 6 is a stopper 7 of cork or rubber which serves the dual purpose of preventing spilling of the liquid when the neck is broken and to protect the liquid from any small particles of glass incident to the fracture of the neck. 55 Disposed in the neck 5 above the stopper 7

and with its lower end slightly below the plane occupied by the groove 6 is a guard stopper 8 preferably of glass. Formed at diametrically opposite points in the periphery of the stopper 8 are grooves 9 which extend longitudinally of the stopper and terminate short of the upper and lower ends thereof. An opening 10 which opens at each end into the corresponding grooves is formed through the guard stopper adjacent its upper 60 end.

A spring wire detent comprises a pair of diverging arms 11 and a connecting portion 12 which latter is engaged in the opening 10 of the stopper 8. The ends of the spring 70 arms 11 are bent outwardly from each other as indicated at 13 and the grooves are of such depth as to receive the said arms entirely therein, the rear wall of each groove being inclined as at 14 for the reception of the bent lower end of its respective arm.

From the foregoing it will be seen that when the guard stopper is inserted in the bottle neck, the arms will spring outwardly for engagement for their bent ends in the 80 groove 6 and that when the neck is fractured the said bent ends will engage the under edge of the separated portion of the neck and thus prevent the same from being fused to the remainder of the neck.

What is claimed, is:—

The combination with a bottle having a grooved neck, of a stopper provided in opposite sides with grooves terminating short of the upper and lower ends thereof, the inner 90 walls of the grooves being inclined with respect to the inner wall of the neck of the bottle, there being an opening formed through the stopper and communicating with the grooves at their upper ends, and a resilient 95 wire member having a connecting portion seated in the opening and spring arms seated in the grooves and having their lower ends bent to extend into the groove in the neck of the bottle, the said bent portions being of 100 greater length than the thickness of the wall of the neck of the bottle whereby upon fracturing of the neck they may engage beneath the fractured end of the said neck.

In testimony whereof, I affix my signature, 105 in presence of two witnesses.

JAMES J. WHITE.
